[57] **CLAIM**

The ornamental design for an ice cream sandwich, substantially as shown and described.

DESCRIPTION

FIG. 1 is a top perspective view of an ice cream sandwich, showing my new design;

FIG. 2 is a top plan view thereof, the bottom view being a mirror image thereof;

FIG. 3 is a front elevation view thereof;

FIG. 4 is a rear elevational view thereof; and

FIG. 5 is a right side elevational view thereof, the left side being a mirror image thereof;

The bottom plan and left side elevational views are mirror images of the opposite views FIGS. 2 and 5 respectively.

FIG. 3

FIG. 4

FIG. 5

FIG. 6

FIG. 7
